UNITED STATES PATENT OFFICE.

WILLIAM A. DOREY, OF NEWARK, OHIO, ASSIGNOR TO HOLOPHANE GLASS COMPANY, OF NEW YORK, N. Y., A CORPORATION OF NEW JERSEY.

LUMINAIRE.

Application filed October 21, 1924. Serial No. 744,881.

To all whom it may concern:

Be it known that I, WILLIAM A. DOREY, a citizen of the United States of America, and a resident of Newark, in the county of 5 Licking and State of Ohio, have invented certain new and useful Improvements in a Luminaire, of which the following is a specification.

The object of this invention is the manufacture of a luminaire of the refractor type, 10 preferably employed in street lighting which can be effectively used at or near the curb, so as to light up the road and street effectively and to keep the neighboring 15 houses either in comparative darkness or to transmit a portion of the light to them for ornamental or utilitarian purposes.

Fig. 1 is a vertical cross section of a 20 luminaire embodying my invention.

Figs. 2 and 3 are diagrams of photometric curves showing the distribution obtained.

Fig. 4 is a vertical cross section of a modified form of luminaire embodying my invention.

Fig. 5 is an end elevation of the inner glass showing a prism modification which may be employed.

In Fig. 1, 1 is a lamp having light source 2 considered as a point. The upper portion 30 of the lamp is enclosed in a compound refracting and reflecting glass consisting of an inner cover 3 and outer cover 8. The inner cover has preferably a smooth inner surface 7, while its outer surface is provided 35 on one half with horizontal refracting prisms 4. The lower part of the other half of the outer surface is provided with radial double reflecting prisms 5, while the upper part of this half is provided 40 with radial double reflecting prisms 6 of greater width and depth than prisms 5 and projected beyond the contour of prism 5. The lower part of this inner cover is made of such a contour that the 45 light striking the reflecting portion will be reflected across the axis of the lamp at wide angles. The upper part is of such a contour that the light striking the reflector side will be reflected across the axis and 50 beneath the opposite edge of the luminaire.

Outer cover 8 has preferably an entirely smooth outer surface 11. The interior surface of one half of 8 is provided with refracting prisms 9 and the interior of the 55 opposite half is provided with horizontal

scattering flutes 10. The covers are placed over each other so that the refracting prisms face each other. That half of the combination which is provided with refracting prisms has its outer surface and both sets 60 of refracting prisms so disposed with reference to each other that they will cooperate with the inner surface which is already determined by the reflecting requirements, in such a way as to refract and 65 transmit the light intercepted by it in a substantially parallel beam slightly below the horizontal. In order that the refracting surfaces may operate throughout the length of the refractor to depress the light and at 70 the same time to permit successful manufacture of the refracting prisms on the outer piece, the lower part of the outer piece is cupped in at 12.

The course of typical light rays is shown 75 to indicate the operation of the various parts of the refractor. The portion of the units having refracting prisms are placed together in the manner shown on the side toward the street, while the portions containing radial reflecting prisms and scattering flutes are placed together toward the houses.

Ray 13 proceeding from the light source is refracted and transmitted as shown in the 80 direction 14. The action of this ray is typical of the action of all rays coming direct from the lamp and intercepted by refracting prisms 4 and 9. Ray 15 will in part be reflected in the direction 16 parallel 85 to emitted ray 14 and will in part be transmitted in direction 17. This is typical of the operation of all light rays direct from the source intercepted by reflecting prisms 5. Ray 20 direct from the source is in part 90 reflected in direction 21, passing beneath the opposite edge of the luminaire at an angle somewhat lower than emitted rays 14 and 16. Ray 20 direct from the source will in part be transmitted in direction 18. This is typical of the action of all light rays 95 direct from the source intercepted by the reflecting prisms 6. The transmitted portion of ray 15 strikes the upper edge of one of the flutes 10. Rays emitted by the source in 100 directions immediately below ray 15 will in part be transmitted to lower portion of this same flute and scattered in directions 19, 19. In the same way the transmitted portion of ray 20 strikes the lower edge of one 110

of the flutes 10 and neighboring rays emitted from the source at an angle above that of ray 20 will in part be transmitted to upper portions of the same flute and scattered 5 in directions 22, 22.

In the description above reference is made to one-half of the unit and the other half of the unit. Of course, this refers to the division of the unit by means of a vertical 10 plane passing through the axis of the lamp. The lateral distribution in any cone will tend to be substantially equal through 180 degrees on the house side but the intensities through the half cone of the house side will differ 15 from the intensities through the half cone on the street side. The vertical distribution on the street side will be similar to typical street lighting distribution intensified by the action of the reflector part but the vertical 20 distribution on the house side will be much lower in intensity at wider angles below the horizontal, some of the upward light being refracted back to the other side and the balance transmitted and scattered in vertical 25 planes.

In Fig. 2 a typical vertical distribution curve 23 for a symmetrical refractor is shown made up throughout in the construction shown at 4 and 9, Fig. 1. Vertical distribution 24 is typical of the combined construction shown in Fig. 1, lobe 25 being that emitted toward the street and lobe 26 being that emitted toward the buildings.

In Fig. 3 a typical lateral distribution curve 27 in a cone 75 degrees from nadir for a symmetrical refractor is shown. Vertical distribution 28 is typical of the combined construction shown in Fig. 1, lobe 29 being that emitted toward the street and 40 lobe 30 being that emitted toward the buildings.

When it is desired to increase the illumination on the buildings the modification shown in Fig. 4 is provided, in which the refracting construction 4 and 9 and the scattering construction 10 are the same as in Fig. 1; also the lower reflecting construction 5 is similar to that in Fig. 1. The upper part of the inner reflecting half is provided on its outer surface with horizontal scattering flutes 31. At 32 are shown bundles of light rays proceeding from the source and intercepted by flutes 31. These rays will be scattered as shown by the flutes 31 and will be given still wider divergence by the flutes 10 on the outer piece so that they will be emitted in directions 33, 33, 33 etc.

The effect of this modification on the distribution of light as illustrated in Fig. 2 will be to decrease slightly the lobe 25 below the point of maximum intensity and to increase lobe 26 above the horizontal. The distribution shown in Fig. 3 will remain substantially the same.

This device may be used within large slightly diffusing enclosing globes and in such cases if the reflecting and refracting parts are divided by a definite division line, the reflector portion will cast a well defined 70 shadow on the enclosing globe when the light source is in operation. Fig. 5 shows an end elevation of the inner glass modified so that the edges of this shadow will be softened. The reflecting prisms 5 and 6 75 immediately adjacent to the refracting prisms 4, are partially cut away at their bases by the refracting sections 34, which are of the same vertical section as refracting prisms 4 and of gradually reducing area as 80 shown. In addition to this, in order to break up the shadow at the lower edge of the glass, refracting sections 35 are provided, cutting the bases of the lower ends of all of the reflecting prisms 5 and each succeeding upward tier of these refracting sections 85 is of reduced area. The action of these refracting sections is to allow gradually decreasing portions of the light striking the edges of the reflector portion to be transmitted and this in effect produces a gradual shading of the edges of the shadow cast 90 upon the enclosing globe.

I claim:

1. A luminaire comprising a light source and a double glass cover enclosing the same, the inner envelope of the cover having on one portion a series of radial double reflecting prisms adapted to reflect the major portion of incident light rays below the lower edge of the opposite side of the unit and opposite thereto a series of horizontal refracting prisms adapted to deflect light downward, the outer envelope of the cover being provided on the portion superimposed above the radial prismatic portion with flutes adapted to scatter the portion of light transmitted by the radial prisms and on the portion superimposed above the refracting prisms of the inner cover with a series of refracting prisms adapted to bend the light downwardly.

2. A luminaire comprising a light source and a double glass cover enclosing the same, the inner envelope of the cover having on one portion of its exterior a series of radial double reflecting prisms adapted to reflect the major portion of incident light rays below the lower edge of the opposite side of the unit and on its exterior opposite thereto a series of horizontal refracting prisms adapted to deflect light downward, the outer envelope of the cover being provided on the portion superimposed above the radial prismatic portion with flutes adapted to scatter the portion of light transmitted by the radial prisms and on the portion superimposed above the refracting prisms of the inner cover with a series of refracting prisms adapted to bend the light downwardly.

3. A luminaire comprising a light source and a double glass cover enclosing the same, the inner envelope of the cover having on one portion of its exterior a series of radial 5 double reflecting prisms adapted to reflect the major portion of incident light rays below the lower edge of the opposite side of the unit and on its exterior opposite thereto a series of horizontal refracting prisms 10 adapted to deflect light downward, the outer envelope of the cover being provided on its interior on the portion superimposed above the radial prismatic portion with flutes adapted to scatter the portion of light transmitted by the radial prisms and on its interior on the portion superimposed above the refracting prisms of the inner cover with a series of refracting prisms adapted to bend the light 15 downwardly.
4. A luminaire comprising a light source, and a double glass cover enclosing the same, the inner envelope of the cover having on one portion near the neck a series of horizontal scattering corrugations and adjacent 20 below a series of radial double reflecting prisms adapted to reflect the major portion of incident light rays below the lower edge of the opposite side of the unit and opposite thereto a series of horizontal refracting 25 prisms adapted to deflect light downward, the outer envelope of the cover being provided on the portion superimposed above the radial prismatic portion with flutes adapted to scatter the portion of light transmitted by the radial prisms and on its interior on the portion superimposed above the refracting prisms of the inner cover with a series of refracting prisms adapted to bend the light 30 downwardly.
5. A luminaire comprising a light source 40 and a double glass cover enclosing the same, the inner envelope of the cover having on one portion of its exterior near the neck a series of horizontal scattering corrugations and adjacent below a series of radial double 45 reflecting prisms adapted to reflect the major portion of incident light rays below the lower edge of the opposite side of the unit and opposite thereto on its exterior a series of horizontal refracting prisms adapted to 50 deflect light downward, the outer envelope of the cover being provided on its exterior on the portion superimposed above the radial prismatic portion with flutes adapted to scatter the portion of light transmitted by the radial prisms and on its interior on the portion superimposed above the refracting prisms of the inner cover with a series of refracting prisms adapted to bend the light 55 downwardly.

Signed at Newark, in the county of Licking and State of Ohio, this 18th day of October, 1924.

WILLIAM A. DOREY.
